UNITED STATES PATENT OFFICE.

FRED STEFFENS, OF ST. JOSEPH, MISSOURI.

ENTRANCE AND EXIT CONTROL AND SIGNAL MECHANISM FOR STREET-CARS.

1,306,786.

Specification of Letters Patent. Patented June 17, 1919.

Application filed October 29, 1917. Serial No. 199,602.

To all whom it may concern:

Be it known that I, FRED STEFFENS, a citizen of the United States, residing at St. Joseph, in the county of Buchanan and State 5 of Missouri, have invented certain new and useful Improvements in Entrance and Exit Controls and Signal Mechanism for Street-Cars, of which the following is a specification.

10 This invention relates to street cars and more especially to controlling gates and signals for one-man cars, and the object is to provide means under control of the motorman for facilitating the orderly and rapid 15 egress and ingress of passengers and preventing entering passengers from obtaining access to the body of the car without giving the motorman an opportunity to see that the fare is paid preliminary to entrance to the 20 body of the car.

A further object is to provide means for automatically signaling passengers ready to enter the car, that the way is clear for entrance.

25 With these objects in view, the invention consists in certain novel and useful features of construction and combinations of parts as hereinafter described and claimed; and in order that the invention may be fully understood, reference is to be had to the accompanying drawing, in which:—

Figure 1, is a horizontal section of the front end of a car equipped with mechanism embodying my invention.

35 Fig. 2, is an enlarged vertical section through the floor of the car to show below the latter a signal mechanism embodying my invention.

Fig. 3, is a detailed plan view of the signaling mechanism.

Fig. 4, is an elevation of the controlling gate of the apparatus.

In the said drawing, 1 indicates the front portion of a street car, and said car is partitioned to provide a passenger compartment or body 2, a motorman's stand 3, and a passage 4, leading from what may be termed the vestibule to the passenger compartment 2, and located at one side of the motorman's stand 3.

50 A hinge post 5, is mounted in the floor of the car in any suitable manner, inward and opposite the center of the opening 6, controlled by the door 7. Said door may be of any suitable type, but preferably is of that class which consists of two members hinged

together at 8, so that when the door is opened by the motorman in any suitable or well known manner, it shall fold and swing to the outstanding position indicated by dotted 60 lines 9, Fig. 1.

Any suitable gate 10, such as the V shaped rod indicated by Fig. 5, is secured to the hinge post to swing therewith, and said gate is adapted to stand obliquely rearward and 65 outward in alinement with a hand-post 11, or obliquely forward and outward in alinement with a hand-post 12, said posts being located respectively near the rear and front sides of the door opening 6. When the gate 70 occupies the position shown by full lines Fig. 1, and the door 7, is open, passengers are free to enter the car and the passageway 4. When the gate occupies the position shown by dotted lines, ingress to the car is prevented but passengers are free to pass out 75 from the passenger compartment between the gate and the hand-post 11. The car will preferably be provided, as customary, with a step (not shown) at the lower end of the 80 door opening.

To control the passage 4, I preferably employ the turnstile 13, of any suitable or preferred type, the same being operated by a handle 14, within convenient reach of the 85 motorman when standing or when seated upon a revolving stool 15. Between the motorman and the gate is a shelf or support 16, which serves as a convenient support for a fare-box 17 or any other accessory. It also 90 constitutes an obstruction to guard against passengers being crowded into the motorman's stand or compartment.

A vertical shaft 18, is suitably journaled and provided with an operating handle 19, 95 within convenient reach of the motorman, and below the floor with a crank 20, pivotally connected by a link rod 21, to a crank 22, secured upon the lower end of the hinge post 5, of the gate, so that movement of said 100 handle 19, shall effect swinging movement of the gate from its full line to its dotted line position and back again.

For the purpose of signaling persons desiring to board the car, that the way is open 105 for their entrance, the crank 22, is provided with a pivoted extension 23, the extension having an arm 24, to abut against the crank 22, when pressed in one direction so that it shall constitute for all intents and purposes 110 a rigid part of said lever, and said extension is adapted to yield when pressed in the op-

posite direction, the arm 24, being connected by a retractile spring 25, with a lug 26, projecting laterally from the crank 22.

Arranged within the swing of the extension crank 22, so as to be operated thereby when the gate swings from the dotted line position to the full line position, is a resilient bell clapper 27, for striking a gong 28, secured and depending from the floor of the car. The clapper is pivoted at 29 at the under side of a plate 30, secured to a block 31, attached to the floor, and a retractile spring 32, connects the clapper with a fixed point of said plate 30, for the purpose of actuating it to strike the gong. By reference to Fig. 3 it will be seen that when the crank 22, swings in the direction indicated by the adjacent arrow, it will engage and operate the bell clapper and that as the extension 23, passes out of engagement with the clapper, the tensioned spring 32, will react and swing the clapper forcibly back with such force that it shall strike the gong for signaling purposes, it being noted that the clapper just before striking the gong comes in contact with the stop pin 33, so that the clapper shall normally be held out of contact with the gong and, furthermore, shall be caused to spring back instantly from the gong after striking it, to avoid deadening the signal.

As the operation of the various parts has been referred to in connection with the description of the construction thereof, no recapitulation is believed to be necessary, and while I have illustrated and described the preferred construction of the invention, it is to be understood that I reserve the right to make such changes in the form, proportion, detailed construction and arrangement of the parts as properly fall within the spirit and scope of the appended claims.

Claims:

1. A street car provided with an entering passage, a passenger compartment, and a door opening; a turnstile controlling communication between the entering passage and said passenger compartment, a gate pivoted within the car between the turnstile and said door opening, and means to swing the

gate to a position where its free end is adjacent one side of the said opening to shut off communication between the same and the body of the car, or shut off communication between said opening and the said entering passage. 55

2. A street car provided with an entering passage, a passenger compartment and a door opening; a door controlling said opening, a gate pivoted within the car opposite the central portion of said door, means to swing the gate to a position where its free end is adjacent one side of said door opening or to a position where its free end is adjacent the other side of said door opening, and a turnstile at the opposite side of the gate from said door, for controlling communication between the said entering passage and said passenger compartment. 65

3. A street car having a door opening at one side of its front end, a swinging gate 70 for adjustment to stand in such relation to the opening that passengers may enter or leave the car through said opening but never at the same time, and means dividing the space between the gate and the closed side of the car at the front end thereof to provide a passageway leading to the interior of the car and an isolated chamber or stand at the closed side of the car, for the motorman. 75

4. A street car having a door opening at one side of its front end, a swinging gate for adjustment to stand in such relation to the opening that passengers may enter or leave the car through said opening but never at the same time, means dividing the space between the gate and the closed side of the car at the front end thereof to provide a passageway leading to the interior of the car and an isolated chamber or stand at the closed side of the car, for the motorman, and a turnstile disposed between said dividing means and the gate for preventing egress from the interior of the car through said passage. 85

In testimony whereof, I affix my signature 95
at St. Joseph, county of Buchanan, State of Missouri, this 22d day of October, 1917.

FRED STEFFENS.

Copies of this patent may be obtained for five cents each, by addressing the "Commissioner of Patents, Washington, D. C."
